John O. Van Koert, New York, N. Y., assignor to Drexel Furniture Company, Drexel, N. C., a corporation of Delaware

Application August 2, 1955, Serial No. 37,260

Term of patent 14 years

(Cl. D33—6)

Fig. 1.

Fig. 2.

The central portion of the dresser has been shown in dotted lines to indicate the dresser may be of varying widths with conventional handle elements also shown in dotted lines. The back of the dresser (not shown) is plain.

I claim:

The ornamental design for a dresser or similar article of furniture, as shown and described.
